UNITED STATES PATENT OFFICE.

JOSEPH H. CHAMP, OF CLEVELAND, OHIO.

TIRE-INFLATER.

SPECIFICATION forming part of Letters Patent No. 691,747, dated January 28, 1902.

Application filed December 7, 1900. Serial No. 39,053. (No model.)

To all whom it may concern:

Be it known that I, JOSEPH H. CHAMP, a citizen of the United States, and a resident of Cleveland, county of Cuyahoga, and State of Ohio, have invented a new and useful Improvement in Tire-Inflaters, of which the following is a specification, the principle of the invention being herein explained and the best mode in which I have contemplated applying that principle, so as to distinguish it from other inventions.

The object of the invention is to provide an improved tire-inflater, especial attention having been given to same in its fitness for use as connected with coin-controlled apparatus.

The nature of the invention consists of the means hereinafter described, and particularly pointed out in the claims.

20 The annexed drawings and the following description set forth in detail certain mechanism embodying the invention, such disclosed means constituting but one of various mechanical forms in which the principle of 25 the invention may be used.

Figure I is a vertical transverse section through the casing of the machine, but without section through the mechanism. Fig. II is a front elevation of the mechanism and 30 showing the casing in vertical section at right angles to the section of the preceding figure. Fig. III is a detail top plan of the twin valve mechanism and certain connecting mechanism. Fig. IV is a front elevation showing 35 certain members of the immediately preceding figure and having the front casing broken away. Fig. V is a detail, partly in vertical section and partly in side elevation, of one of the twin valve mechanisms shown in the 40 immediately preceding figure. Fig. VI is a sectional detail of a portion of the coin-controlling mechanism. Fig. VII is a sectional detail at right angles to the plane in which the immediately preceding figure is taken. 45 Fig. VIII shows the check-valve mechanism in different views. Fig. IX is a detail top plan of fluid connections of the expansion-cylinder. Fig. X is a detail, mainly in vertical section, of fluid connections of the expansion-cylinder. Fig. XI is a detail view, 50 partly in vertical section and partly in side elevation, of the automatic cut-off between

the expansion-cylinder and the tire-feed nozzle. Fig. XII is a detail view, in side elevation, showing the bearing of the tire-feed nozzle in the casing. Fig. XIII is a detail view in perspective of the tire-feed nozzle and its connections.

The casing A may be of any suitable construction, its purpose being to exclude the public from access to the inclosed mechanism and also to protect the latter from the weather. It is preferably provided at its rear with a door a, whereby privileged access may be had to its interior. Two upright cylinders B C are provided, the one, B, being a storage-cylinder of compressed carbonic-acid gas, the other, C, being an expansion-cylinder. These two cylinders respectively communicate by tubes b c with the pressure-regulator D, having a gage-dial d subject to conditions adapted to automatically cause gas from the storage-cylinder to pass under a predetermined pressure into the expansion-cylinder.

A tube e carries the gas from the top of expansion-cylinder C to the lower portion of valve-cylinder E, wherein communication with tube f, connected with the upper portion of said cylinder, is controlled by a valve having a tendency to be maintained in raised position by a spring, such raised position of the valve shutting off communication within the valve-chamber between said tubes e and f. The mechanism of this valve-cylinder E is a 80 duplicate of the mechanism of valve-cylinder G, hereinafter referred to, and the interior construction of each is shown by the single view of Fig. V. Said tube f is also connected with the upper portion of an initial power-reservoir F at one side thereof, the upper portion of the opposite side of such reservoir connecting with one extremity of a tube g; the opposite extremity of said tube g connecting with the lower portion of valve-cylinder G, such cylinder G being of construction and having an inclosed upwardly spring-pressed valve, such as shown in Fig. V, the upper portion of such cylinder G connecting by tube h with the casing-inclosed end portion 90 of rock-tube H, which latter has its opposite end portion projecting out through the lower portion of the front wall of casing A.

Each of the twin valve-cylinders E and G

has a pivoted angular lever whose lower side engages with the top of a valve-stem, each such pivotal lever being adapted to be depressed by a cam carried on the lower side of 5 horizontal slide J, the opposite end portions of the latter having free sliding movement in bearing-boxes j. Said lever, stem, and cam connected with cylinder E are respectively lettered as k l m, while the corresponding 10 members connected with cylinder G are respectively lettered as n o p.

Rock-shaft K has a sleeve L fitted thereon and adjustably clamped thereto by a set-screw r, such sleeve having a weighted rigid arm M. 15 Said sleeve is further provided with a rigid arm s, adapted to work freely within a slot t, formed in a horizontal plate N, located beneath the horizontal slide J. The rock-shaft is adapted to be rocked toward the right by 20 a rod P, which depends by pivotal connection from arm M, the lower end of such rod being connected to rigid arm v, projecting right angularly from the easing-inclosed end portion of rock-tube H, the opposite and outer projecting extremity of such rock-tube being provided with a rigid arm w, projecting right angularly therefrom in direction opposite to the projection of arm v, the outer extremity of 25 such arm w being provided with an upwardly-projecting tire-feed nozzle x.

The inner extremity of rock-tube H is connected in common to the lower extremities of the three several tubes h y z. The upper portion of tube y connects with the upper portion 35 of chamber R, above diaphragm a', located horizontally across said chamber. The central portion of the lower side of said diaphragm has bearing against stem b', which depends through the lower portion of said chamber R, the inclosed portion of such stem being 40 encircled by a spiral spring c', compressed between said diaphragm and cap d', detachably fitting in the lower portion of said diaphragm-chamber. The lower end of said stem b' projects below said cap and has loose bearing 45 upon the free extremity of angular lever e', pivoted to the upper portion of valve-chamber S, said lever resting in loose bearing upon valve-stem f', which projects through the top 50 of said valve-chamber S. Said valve-stem has its lower extremity connected to valve g', which is upwardly spring-pressed by spring h' and controls communication between the 55 upper extremities of tubes z and j', respectively, at different horizontal points. The lower and opposite extremity of said tube j' communicates with the top of expansion-cylinder C. Tube h is provided with valve mechanism l', adapted to permit gas to pass downwardly through same, but to prevent upward return passage of such gas.

A coin-slot m' is in the upper portion of the 60 front wall of the casing and connects with a coin-chute T. The slide J has its approximately middle portion provided with a transverse receptacle n' of size adapted to receive

a desired coin above the horizontal plane of plate N, that portion of slide J adjacent to said coin-receptacle n' being formed in open 70 box form p' to permit the free upward projection therein of arm s. Said coin-receptacle n' has its lower central portion formed with a slot r' of size suitable to permit arm s to work freely therein when there is no coin 75 in receptacle n'; but when a coin has entered receptacle n' such coin may drop of its own weight and edgewise onto plate N and there remain as a barrier against the passage of arm s through slot r', such arm then bearing 80 against the face of the coin when force is exerted to rock said arm toward the right and the coin thus serving as a mechanical member to cause slide J to be correspondingly moved to the right until the coin has reached 85 a vertical plane to the right of plate N. The coin then, being freed from the support of said plate, falls of its own gravity into chute V and is therefrom dropped into cash-box W.

Arm s is provided at its upper left portion 90 with a finger s' of size and shape such that the entire finger can never be to the right of the vertical plane passing through coin-receptacle n'. This prevents the possibility of a coin being introduced into said receptacle 95 when arm s is to the right of a vertical plane passing through such receptacle under such conditions as to prevent said arm from being readily thrown back to the left when rock-shaft K is released by the bicyclist and is 100 subject to the return action of weighted arm M. Padded bumpers X are provided for weight Y to strike against at the extremes of its movement.

The operation of the machine is as follows: 105 The bicyclist slips a suitable coin into slot m', whence the coin passes down along chute T and into coin-receptacle n'. He removes the cap from the nipple of his wheel-tire and places the latter on the tire-feed nozzle x, with the opened nipple fitting in the open end of such nozzle, the mouth of the latter being of size and shape adapted to effect substantially a gas-tight joint with such open nipple of a wheel-tire. The weight of the 110 wheel causes rock-tube H to rock to the right, so as to move rod P upwardly, thereby causing arm M to rock the shaft K to the right and cause arm s to bear against the coin in receptacle n', so as to throw slide J toward the 115 right, thereby causing cam m to be disengaged from lever k, so as to permit the upward spring-pressed valve in cylinder E to rise and close communication between tubes e and f, and simultaneously therewith cam p depresses lever n, which latter depresses the upwardly spring-pressed valve in cylinder G, thereby establishing communication between tubes g and h. Communication of gas from 120 initial power-reservoir F being had, through tube g and valve-chamber G, with tube h by reason of said movement of slide J toward the right, such gas under pressure passes into rock-tube H. At the same time the gas passes 125 130

by tube *y* into the upper portion of diaphragm-chamber *R*, thereby depressing diaphragm *a'* and causing stem *b'* to depress lever *e'*, the latter depressing stem *f'*, which depresses valve *g'*, thereby causing tubes *j'* and *z* and valve-chamber *S* to permit expansion-cylinder *C* to be in open communication with rock-tube *H*. The tire is thereupon inflated to such full degree of pressure as the bicyclist may desire, whereupon he lifts his wheel from the nozzle *x*. The weight *Y* is then sufficient to rock the shaft *K* toward the left, at the same time carrying rod *P* downwardly and rocking the tube *H* so as to bring arm *w* again into horizontal position. Such rocking of shaft *K* throws slide *J* toward the left as arm *s* bears against the left wall of box-opening *p'*. Cam *p* is thereby disengaged from lever *n*, so as to permit the upwardly-spring-pressed valve in cylinder *G* to rise and close communication between tubes *g* and *h*, and simultaneously therewith cam *m* depresses lever *k*, which latter depresses the upwardly-spring-pressed valve of cylinder *E*, thereby establishing communication between tubes *e* and *f*. Gas thereupon passes from expansion-cylinder *C* into the initial power-reservoir *F*, filling the latter and also tube *g*, leading therefrom to cylinder *G*; but by reason of the communication being closed between tubes *g* and *h* the gas is maintained under pressure in the initial power-reservoir *F* until a further proper coin is inserted in the coin-slot, whereupon the operation heretofore described is repeated.

The invention accomplishes the valuable result of rendering it necessary that before gas can be taken from the tire-feed nozzle to inflate any certain tire a corresponding coin must be introduced in the coin-slot. No tire can be fraudulently filled from the machine. The diaphragm *a'* is sufficiently relieved from gas-pressure upon its surface immediately upon the removal of one tire from the tire-feed nozzle, which removal destroys the pressure existing in the tube *y* when the tire is on said nozzle, so that the valve *g'* thereupon instantaneously closes communication between tubes *z* and *j'*, thus rendering it impossible for gas to again pass from expansion-cylinder *C* through the latter tubes into rock-tube *H* until a further coin has been deposited in the coin-slot and the previously-described operation repeated.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention—

1. The combination of a large fluid-chamber, a small fluid-chamber, a third chamber and a movable member therein, a tire-feed device, two fluid-ways, one of said ways providing fluid communication between said

small chamber and said third chamber and having a valve which controls said communication, the other one of said ways providing fluid communication between said large chamber and said tire-feed device and having a valve which controls said communication, a mechanical connection between the latter valve and said movable member in said third chamber, substantially as set forth. 70

2. The combination of a large fluid-chamber, a small fluid-chamber, a tire-feed device, a fluid-way providing fluid communication between said large chamber and said tire-feed 80 device and having a valve which controls said communication, a diaphragm mechanically connected with said valve, a chamber within which said diaphragm is located, a fluid-way providing fluid communication between said 85 small fluid-chamber and said diaphragm-chamber and having a valve which controls said communication, substantially as set forth.

3. The combination of a large fluid-chamber, a small fluid-chamber, a third chamber and a movable member therein, a tire-feed device, three fluid-ways, one of said ways providing fluid communication between said large and small chambers and having a valve 90 which controls said communication, another one of said ways providing fluid communication between said small chamber and said third chamber and having a valve which controls said communication, the remaining one 95 of said ways providing fluid communication between said large chamber and said tire-feed device and having a valve which controls said communication, a mechanical connection between the latter valve and said 100 movable member in said third chamber, substantially as set forth.

4. The combination of a large fluid-chamber, a small fluid-chamber, a tire-feed device, a fluid-way providing fluid communication 110 between said large chamber and said tire-feed device and having a valve which controls said communication, a movable member mechanically connected with said valve, a chamber within which said movable member 115 is located, a fluid-way providing fluid communication between said small fluid-chamber and said tire-feed device and said movable-member chamber and having a valve which controls said communication as between said 120 small fluid-chamber on the one hand and said tire-feed device and said movable-member chamber on the other hand, substantially as set forth.

5. The combination of a large fluid-chamber, a small fluid-chamber, a third chamber and a diaphragm therein, a tire-feed device, four fluid-ways, one of said ways providing fluid communication between said large and small chambers and having a valve which controls 125 said communication, a second one of said ways providing fluid communication between said small chamber and said tire-feed device and having a valve which controls said com- 130

- munication, a third one of said ways providing communication between said tire-feed device and said diaphragm-chamber, a fourth one of said ways providing fluid communication between said large chamber and said tire-feed device and having a valve which controls said communication, a mechanical connection between the latter valve and said diaphragm, substantially as set forth.
6. The combination of a fluid-chamber, a movable tire-feed device, a fluid-way providing fluid communication between said chamber and said movable tire-feed device and having a valve which controls said communication, a movable member mechanically connected with said valve, a chamber within which said movable member is located, a fluid-way providing fluid communication between said movable-member chamber and a source of fluid-supply and having a valve which controls said communication, mechanism connecting said movable tire-feed device and said last-named valve whereby movement of said tire-feed device operates said last-named valve, substantially as set forth.
7. The combination of a large fluid-chamber, a small fluid-chamber, a fluid-way which provides fluid communication between said chambers and has a valve which controls said communication, a movable tire-feed device, a fluid-way which provides fluid communication between said small chamber and said movable tire-feed device and has a valve, mechanism connecting said movable tire-feed device and said two valves, said members constructed substantially as set forth whereby movement of said tire-feed device operates said valves, substantially as set forth.
8. The combination of a large fluid-chamber, a small fluid-chamber, a third chamber and a movable member therein, a movable tire-feed device, two fluid-ways, one of said ways providing fluid communication between said small chamber and said third chamber and having a valve which controls said communication, the other one of said ways providing fluid communication between said large chamber and said movable tire-feed device and having a valve which controls said communication, a mechanical connection between the latter valve and said movable member in said third chamber, mechanism connecting said movable tire-feed device and said valve which controls fluid communication between said small chamber and said third chamber whereby movement of said tire-feed device operates said last-named valve, substantially as set forth.
9. The combination of a large fluid-chamber, a small fluid-chamber, a movable tire-feed device, a fluid-way providing fluid communication between said large chamber and said movable tire-feed device and having a valve which controls said communication, a diaphragm mechanically connected with said valve, a chamber within which said diaphragm is located, a fluid-way providing fluid commu-

nication between said small fluid-chamber and said diaphragm-chamber and having a valve which controls said communication, mechanism connecting said movable tire-feed device and said last-named valve whereby movement of said tire-feed device operates said last-named valve, substantially as set forth.

10. The combination of a large fluid-chamber, a small fluid-chamber, a movable tire-feed device, a fluid-way providing fluid communication between said large chamber and said movable tire-feed device and having a valve which controls said communication, a movable member mechanically connected with said valve, a chamber within which said movable member is located, a fluid-way providing fluid communication between said small fluid-chamber and said tire-feed device and said movable-member chamber and having a valve which controls said communication as between said small fluid-chamber on the one hand and said tire-feed device and said movable-member chamber on the other hand, mechanism connecting said movable tire-feed device and said last-named valve whereby movement of said tire-feed device operates said last-named valve, substantially as set forth.

11. The combination of a large fluid-chamber, a small fluid-chamber, a third chamber and a movable member therein, a movable tire-feed device, three fluid-ways, one of said ways providing fluid communication between said large and small chambers and having a valve which controls said communication, another one of said ways providing fluid communication between said small chamber and said third chamber and having a valve which controls said communication, the remaining one of said ways providing fluid communication between said large chamber and said tire-feed device and having a valve which controls said communication, a mechanical connection between the latter valve and said movable member in said third chamber, mechanism connecting said movable tire-feed device and said valve which controls fluid communication between said large and small chambers whereby movement of said tire-feed device operates said last-named valve, substantially as set forth.

12. The combination of a large fluid-chamber, a small fluid-chamber, a third chamber and a movable member therein, a movable tire-feed device, four fluid-ways, one of said ways providing fluid communication between said large and small chambers and having a valve which controls said communication, a second one of said ways providing fluid communication between said small chamber and said movable tire-feed device and having a valve which controls said communication, a third one of said ways providing communication between said movable tire-feed device and said third chamber, a fourth one of said ways providing fluid communication between

said large chamber and said tire-feed device and having a valve which controls said communication, a mechanical connection between the latter valve and said movable member in said third chamber, mechanism connecting said movable tire-feed device and said two first-named valves whereby movement of said

tire-feed device operates said two first-named valves, substantially as set forth.

Signed by me this 5th day of December, 1900.
